UNITED STATES PATENT OFFICE.

KARL AUGUST BRÄUNING, OF HERSTAL, BELGIUM.

FIRING MECHANISM FOR AUTOMATIC FIREARMS.

1,073,588.

Specification of Letters Patent. Patented Sept. 23, 1913.

Application filed July 16, 1912. Serial No. 709,811.

To all whom it may concern:

Be it known that I, KARL AUGUST BRÄUNING, a subject of the Emperor of Germany, and resident of Herstal, in the Kingdom of Belgium, have invented certain new and useful improvements in Firing Mechanism for Automatic Firearms; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

The present invention relates to a firing mechanism for automatic firearms in which the percussion bolt is provided with a part subjected to the action of a spring which part comprises the sear retains the percussion bolt or hammer in the cocked position by striking against a stop on the breech bolt, the firing being effected by releasing the engagement of the said part and the stop.

The invention relates particularly to the means serving for actuating the sear.

An embodiment of the invention as applied to an automatic gun is illustrated in the accompanying drawing, in which:

Figure 1 illustrates the parts when the gun is ready for firing. Fig. 2 represents the parts during the recoil of the breech bolt and indicates how the hammer is cocked. Fig. 3 illustrates the position of the parts immediately after firing when the percussion bolt is again cocked by the automatic mechanism, but before the marksman has released the trigger. Fig. 4 is a section in line A—B of Fig. 1. Figs. 5 and 6 are a vertical longitudinal section and a plan view respectively of the breech bolt. Fig. 7 is an elevation of the percussion hammer. Fig. 8 is a section in the line C—D of Fig. 7, looking toward the left. Fig. 9 is a section in the lines E—F of Fig. 7, looking toward the right. Figs. 10 and 11 are detail views showing the member which cocks the hammer. Figs. 12, 13 and 14 show the sear which maintains the hammer cocked.

The hammer 1 is forced forward by the spring 2 which bears at 35 on the abutment 25 on the hammer 1. Pivotally mounted on the hammer at 3 is a sear 4 the rear face of which is engaged by the spring 2 in such manner that its nose or forward end is nor-

mally depressed by the spring. When the hammer 1 is cocked the sear 4 engages at 6 with the breech bolt 8. When the sear 4, the upper part 26 of which enters into a corresponding groove 37 of the hammer, is raised, the abutment 6 is released and the freed hammer is carried forward and carries along the sear 4 which is then displaced in the groove 7 of the breech bolt. During this displacement, the lugs 38 of the abutment of the hammer slide along the surfaces 39 of the rear part of the breech bolt. In the position which it occupies after the forward movement, the abutment 25 rests against a part 26 which serves to recock the hammer. The two arms 27 of this part 26 are disposed on either side of the hammer and within the hollow part 40 of the breech bolt; the pivots 28 of this part are positioned in the grooves 29 of the breech bolt. The two projections 30 of the part 26 abut against the corresponding lugs 31 of the walls of the breech-box or frame and compel this part 26 to turn on its pivots 28 until the plane surfaces of the lugs 30 rest on the surfaces 39 of the lock. The ends of the arms 27 rest during this rotation against the abutment 25 of hammer 1 and thus cause the same to be displaced with respect to the breech bolt 8, against the action of the spring 2. When the part 26 has taken the position illustrated in Fig. 2, the sear 4 is released from groove 7 and takes the position shown at Fig. 2, in consequence of the action of spring 2 which presses toward the rear against the bottom of a housing 32 attached to breech bolt 8. The breech bolt continues its recoil movement, the lugs sliding in the grooves 42 of the breech-box; subsequently, under the action of the recuperative spring 41, it retakes the position shown in Fig. 1. On the other hand, during the closing movement of the lock, lugs 30 of the part 26 abut against the oblique lugs 34 of the breech-box and cause this piece 26 to retake its original position. During this time the hammer is not any more in contact with arms 27 and advances until the sear 4 engages the lock at 6, while the lock passes from the position of Fig. 2 to the position of Fig. 3. The hammer 1 is then again recocked.

This invention relates more particularly to the arrangement serving for lifting the part 4 and which is of such a nature that it is possible to recock the percussion bolt

when the marksman has not released the trigger 9. This trigger 9 which is pivotally mounted on the frame is subjected to the action of a spring 11. The trigger carries a stud 14 which enters the fork 15 of a lever 16 and ends in front in a hook-like arm 17 which engages in an opening 18 in the lever 16. Rearwardly the opening 18 comprises a vertical face 23 which ends below in a rearwardly inclined face 24. In the lever 16 a slot 19 is provided in which a shaft 20 rigidly connected with the frame engages. In front the lever 16 has a perpendicular arm 21 adapted to lift the part 4 by the intermediary of the nose 22.

When the parts assume the position illustrated in Fig. 1 and the trigger 9 is actuated, the rear part of the lever 16 is depressed by the stud 14 and the arm 21 is lifted against the nose 22 of the part 4. During this operation the hook 17 alters its position in front of the vertical face 23 in such a manner that it is quite impossible for the lever to move forward. On continuing to actuate the trigger 9 the arm 21 lifts the part 22 and produces firing. During this time the hook 17 will have been lowered to such an extent that it is brought in front of the inclined face 24 and out of contact with this face. After firing the percussion bolt resumes its original position, the nose 22 strikes the arm 21 which is still maintained raised and draws it forward into the position shown in Fig. 3 until the hook 17 encounters the lower part of the inclined face 24. When the marksman releases the trigger 9 the latter resumes its initial position under the influence of the spring 11 whereby the hook 17 is lifted and the nose 21 depressed by the stud 14. The action of the hook 17 on the inclined face 24 carries the lever 16 rearward whereby finally all the parts are returned to the position shown in Fig. 1.

Claims:

1. In a firing mechanism for automatic firearms, the combination of a percussion bolt, a pivotally mounted sear on the percussion bolt, a stop for said sear upon the breech bolt, a sliding lever provided with an arm lifting this sear when firing, a trigger actuating this lever and means for disengaging the arm of said lever from the pivotally mounted sear by the action of the trigger, at the moment at which it is released by the marksman. 45

2. In a firing mechanism for automatic firearms, the combination of a percussion bolt, a pivotally mounted sear on the percussion bolt adapted to engage with the breech bolt, a sliding lever provided with an arm lifting said sear when firing, a trigger actuating said lever by means of a stud engaged between forks of the lever, and means for disengaging the arm of said lever from the pivotally mounted sear by the action of the trigger at the moment at which it is released by the marksman. 50

3. In a firing mechanism for automatic firearms, the combination of a percussion bolt, a sear pivotally mounted on the percussion bolt, a stop for said sear upon the breech bolt, a lever provided with an arm lifting said sear when firing, a trigger actuating said lever by means of a stud engaged between forks of the lever, a nose of the trigger acting on an inclined face of the lever in such a manner that it disengages the lever arm from the sear at the moment at which said trigger is released by the marksman. 55

In testimony whereof I affix my signature in presence of two witnesses.

KARL AUGUST BRÄUNING.
